UNITED STATES PATENT OFFICE.

EDWARD ZUVER LEWIS, OF CHICAGO, ILLINOIS.

MANIFOLD ATTACHMENT FOR TYPE-WRITERS.

1,258,421.

Specification of Letters Patent.

Patented Mar. 5, 1918.

Application filed December 16, 1916. Serial No. 137,414.

To all whom it may concern:

Be it known that I, EDWARD Z. LEWIS, a citizen of the United States, and a resident of Chicago, in the county of Cook and State 5 of Illinois, have invented certain new and useful Improvements in Manifold Attachments for Type-Writers; and I do hereby declare that the following is a full, clear, and exact description thereof, reference being had to the accompanying drawings, and to the letters of reference marked thereon, which form a part of this specification.

This invention relates to an attachment for typewriters adapted for making manifold copies easily and conveniently, without the insertion of carbon sheets or the jogging or shifting of the manifold sheets and carbon sheets to make the carbon copies register, as is required in ordinary methods. The 10 invention consists of the matters hereinafter described and more particularly pointed out in the appended claims.

The attachment is particularly intended for making manifold copies on forms printed 15 on a continuous sheet folded lengthwise and comprised of a plurality of superposed sections, the number of sections depending upon the number of carbon copies or duplicates required. The continuous folded sheet 20 is in the form of the commonly known "fan-fold" or "accordion fold" and the forms are printed successively and identically in succession upon the several folded sections of the sheet.

The invention relates more particularly 25 to a typewriter attachment which includes and provides a support for the carbon sheets or ribbons by means of which the manifold copies are made and the object of the invention is to provide such an attachment in which the carbon sheets or ribbons are so arranged and so connected to the platen of the typewriter that a continuous folded sheet 30 of the kind described, that is to say, a sheet folded in a "fan-fold" or "accordion-fold" may be automatically interleaved with the carbon sheets as the carbon sheets are wound upon the platen in the operation of the typewriter and will be automatically delivered 35 and diverted from the carbon sheets after the typewriting operation is finished.

The various advantages of my invention will be more clearly pointed out as I proceed with my specification.

In the drawings:

55

Figure 1 is a view representing in front elevation a typewriter provided with my improved attachment.

60

Fig. 2 is a view representing the same inside elevation.

Fig. 3 is a view representing in perspective a sheet of paper folded longitudinally in a fan or accordion fold and then folded as a whole upon itself in a zigzag fold in a familiar manner for feeding to the typewriter. 65

Fig. 4 is a view representing in perspective one of the parts of my improved attachment.

70

Fig. 5 is a view representing in detail a top plan view of one end of the attachment.

Fig. 6 is a view representing a transverse section through Fig. 4 in a plane indicated by the line 6-6 thereof.

75

Fig. 7 is a view representing a section through Fig. 5 in a plane indicated by the line 7-7 of Fig. 5.

80

Fig. 8 is a view representing, on an enlarged scale, a partial section through Fig. 1 in a plane indicated by the line 8-8 of Fig. 1.

Fig. 9 is a diagrammatic perspective view representing the manner in which the carbon ribbon or carbon papers are arranged and wound about the platen.

Fig. 10 is a diagrammatic sectional view 85 in a plane indicated by the line 10-10 of Fig. 9.

Referring now to that embodiment of my invention illustrated in the drawings:—11 indicates a typewriter which may be of any usual or familiar construction, but which in the present case is shown as a visible writing machine and in particular, a "Monarch" machine. 12 indicates the paper carriage thereof which is adapted to travel transverse 90 the machine in the manner and for the purpose well known. As shown, said paper carriage has a rear frame member 13 which is suitably mounted on antifriction elements between the top and bottom carriage rails 100 11^a, 11^b, and said rails are supported in place on overhanging brackets 14 arising from the top of the machine frame near its rear edge. 15 indicates the usual platen which has rotative bearings in the end members of the paper carriage and which may be rotated by means of the platen knob 15^a which in this instance is only one in number and pref-

erably at the right hand end thereof. The usual paper tension devices 16 are provided for and at the left hand end of the platen is provided the usual lever operated mechanism 5 17 (see Fig. 1) by means of which the platen is rotated to feed it in a step by step movement every time the platen is shifted toward the right to present a new line space to be written upon. 18 indicates the usual ribbon 10 and its associated mechanisms which raise it to the level of the printing line of the platen when any one of the key levers are depressed. As my attachment is mounted entirely upon and moves with the paper carriage, it is 15 thought that a further description of the mechanism and operation of the typewriting machine proper will be unnecessary.

20, 21 indicate frame members which are adapted to be attached to the paper carriage 20 frame preferably at the ends thereof. Each frame as shown is adapted to receive and provide supporting bearing for associated tubular spools 22, 23 which are arranged to extend radially upwardly and rearwardly 25 from the longitudinal axis of the platen 15. As shown (see Figs. 1, 2 and 4) each frame is made of comparatively thin sheet metal stamped and formed into the desired shape. As said frames 20, 21 are identical in form 30 with the exception of being left and right, that one, the one 20 adapted to be attached to the left hand end of the paper carriage (see Fig. 4) will be described in detail.

The said frame 20 comprises a vertically 35 arranged plate 25 by means of which it is attached to the end and rear members of the paper carriage frame and spaced upright bars 26, 26, said bars being connected together at their top ends by means of a horizontal transverse bar or strip 27. 30, 30 and 31, 31 indicate pairs of relatively short and long longitudinally extending top and bottom bars, which project laterally from the uprights 26 toward the opposite frame 20 40 (21). The ends of said bars 30, 31 are joined together by means of inclined bars 32 which are of narrower width than the bars 30, 31 so as to form shoulders 32^a, 32^b adjacent their ends for a purpose which will 45 presently appear, said bars being arranged at an angle approximately 45°. Brace bars 33, 33 connect said bars 31, 31 and 32, 32 intermediate their ends. At the top and bottom of the upright bars 26 are inwardly 50 projecting flanges 34, 35 which are formed by bending over suitable punched out portions of the sheet of metal from which the frame as a whole is made. Said flanges provide a bearing support for the associated tubular spool 22 (23) in the following manner.

The spool 22 (23) is of a length approximating the distance between said flanges 34, 35 and it is provided at its ends with trunnions 22^a (23^a) which are adapted to engage

in slots 34^a, 35^a formed in the free ends of said flanges. 36, 36 indicate adjustable bearing devices for said trunnions. Each device comprises a threaded shank 36^a which is arranged to project through an upright bar 70 37 punched out of the flanges 34, 35, and an eye 36^b which is adapted for engagement with said trunnions. A thumb nut 38 is provided on each adjustable bearing device 36 and a collar 39 is interposed on the trunnion 22^a between the flange 34 and the top 75 of the associated spool 22 to prevent endwise shifting of the spool. It is apparent that tightening or loosening the thumb nuts 38 on the threads of associated shanks 36^a the 80 top and bottom trunnions of the spool may be adjusted laterally and a proper tension imposed on a transfer means which will be presently described.

The bracket frame 21 fixed to the right 85 hand end of the carriage frame is preferably arranged with its bars 31, 32 between the like bars of the bracket frame 20. The rear top bars 30, 30 of the frames 20, 21 are connected together by means of a rod 40 and the front top bars 30, 30 of the frame 20, 21 are connected in a similar manner by means of a flat bar 41 which is fixed at its ends to said top bars. The flat bar 41 is provided with a pair of longitudinally extending slots 90 41^a, 41^b and that part of said bar between said slots is punched or displaced rearwardly. The top edge of said flat bar constitutes a tearing edge for a purpose as will presently appear.

50, 51 indicates transfer means which may be made of any suitable material such as carbon paper or inked ribbon, there being one of such transfer means associated with each frame 20, 21. As shown (see Figs. 1 105 and 9) said transfer means are in the form of wide endless belts or loops which pass around the platen 15 together in vertically arranged front and rear laps 50^a and 51^a, 110 which are diverged from the vertical by being passed over and about the inclined bars 32 of the frames 20, 21, so as to extend in a horizontal plane toward and about the associated upright spools 22, 23, in each of said frames. This divergence of each belt or loop 115 of transfer means is made in the familiar manner known as the "quarter turn belt" and in this case the shoulders 32^a on the bars 32 retain the laps of the loop in their proper positions. As will be apparent from an inspection of Fig. 9 of the drawing, the front vertical laps will always travel upward from the platen when the same is rotated in the direction of the arrows at the 120 ends thereof and the front horizontal laps will travel outwardly where they will then engage the associated spools to be directed horizontally inward in their travel, making the quarter turn about the bars 32 of their 125 associated frames to be diverged in a quar-

ter turn vertically downwardly in alignment about the platen and upwardly as before, this constituting the cycle of movement of the various laps of the transfer means.

In Fig. 3 is illustrated the manifold paper in its preferred form which is adapted for use in connection with my improved attachment. It is preferably folded the length 10 of the sheet to provide three plies or superposed sections 55, 56, 57, the outermost sections 55, 57 being folded to extend in opposite directions as in a flattened letter S. For convenience, I also find it advisable to 15 fold the "fan-folded" strip, transversely of its length, back and forth upon itself so that it may be easily fed between the transfer means in a manner to be described, without the liability of crimping of the lateral 20 edges of the folded strip, which would occur if it were fed from a reel into and between the transfer means. Upon the superposed faces 55^a, 56^a, 57^a, of each section of the strip will be printed (preferably in a 25 light colored ink) such data as is necessary for the headings and directions, etc., said headings and directions, etc., appearing in successive spaced relation throughout the length of the strip.

30 In feeding or threading the strip into or between the transfer means and about the platen, it is first passed over the bar 40 connecting the two frames 20, 21 together at the rear, with the printed surface of said 35 strip facing toward the rear or away from the operator, after which it is directed downwardly toward the vertically traveling laps of the transfer means, with the section 55 toward the operator. The intermediate section 56 is thus located between the rear vertical laps of the transfer means with the section 55 in front of the front vertical lap of the transfer means and the section 57 to the rear of the rearmost lap of the transfer 45 means. The turning knob of the platen is turned to rotate the platen to feed the various laps of the transfer means as before described, said transfer means carrying with it the various sections of the manifold strip 50 about the platen. In the preliminary insertion feed of the manifold strip into and through the attachment, it is fed a sufficient length beyond the platen so that the free end of said length may be threaded through and 55 a short distance beyond the slots in the bar 41 connecting the frames 20, 21 together at the front. This brings the printed faces 57^a, 56^a, 55^a of the various superposed sections toward the front and in the order mentioned.

60 The order of superposition about the platen of the manifolding sheet and transfer means will be, the section 55 next to the platen, the vertical lap 51^a of the transfer means associated with the frame 21, next to the intermediate section 56 of the manifold strip,

then the lap 50^a of the transfer means and finally the section 57 of the manifold strip, which is adapted to receive the original impression from the inked ribbon 18 of the typewriting machine proper.

70

As an example of the operation of the attachment in the use of making waybills or bills of lading, such as are used by the railroad companies, it is of course known that on one bill only a few items may appear and 75 on other bills a great many items may appear. I will describe the manner of making a bill of lading containing a large number of items or articles thereon.

In the proper heading, the operator will 80 write the proper name and address with the various directions. In itemizing the articles, should they take up more room than the distance between each successive printed form, the operative continues to write the articles 85 over the next successive printed heading and as said headings are printed in a light colored ink, the inscription made by the operator will predominate so as to be easily visible even when inscribed directly upon the printed heading. When the successive bills are 90 made up, each separate and complete bill is torn from the strip at the tearing edge provided therefor on the bar 41.

If the items written upon the strip do not 95 take up the space between the successive headings thereon, the strip is torn off as before described and thus a short bill is had.

It is apparent that a long or a short bill 100 may be had as the occasion demands and thus a great saving of time and labor is had over the old style of bills where a separate bill of the proper length has to be inserted into a typewriting machine for each bill made out.

I claim as my invention:

135

1. In a typewriting machine, a paper carriage including a platen, a transfer member supporting frame mounted on said carriage, said frame having members which are arranged substantially parallel with the platen 110 and members which are angularly arranged relative to said platen, said last mentioned members acting to guide said transfer member so that parts thereof are positively directed to move toward, about and 115 away from said platen and so that other parts thereof are positively directed in a certain manner after passing around the platen, to move in opposite directions, in a plane parallel to the platen, in the turning movement of said platen.

2. In a typewriting machine, a paper carriage including a platen, transfer members supporting frames mounted on said carriage, said frames having members which are arranged substantially parallel with the platen 125 and members which are angularly arranged relative to said platen, said last mentioned members acting to guide said transfer members so that parts thereof are positively di- 130

rected to move toward, about and away from said platen and so that other parts thereof are positively directed in a certain manner after passing around the platen, to move in opposite directions in a plane parallel to the platen, in the turning movement of said platen.

3. In a typewriting machine, a paper carriage including a platen, transfer members supporting frames mounted on said carriage, said frames having members which are arranged substantially parallel with the platen and members which are angularly arranged relative to said platen, said last mentioned members acting to guide said transfer members so that parts thereof are positively fed about the platen in superposed relation, and so that other parts thereof are fed in a plane parallel to the platen in the turning movement of said platen.

4. In a typewriting machine, a paper carriage including a platen, transfer members supporting frames mounted on said carriage, said frames having members which are arranged substantially parallel with the platen and members which are angularly arranged relative to said platen, said last mentioned members acting to guide said transfer members so that parts thereof are positively directed to move in superposed relation toward, about, and away from said platen, and so that other parts thereof are positively directed in a certain manner after passing around the platen, to move in opposite directions in a plane parallel to the platen, in the turning movement of said platen.

5. In a typewriting machine, a paper carriage including a platen, a framework mounted on the carriage and constructed to support a plurality of endless transfer members, which are adapted for a feeding movement with and about said platen, said framework guiding said transfer members so that parts thereof move toward and away from the platen in superposed relation, said framework including means which direct the superposed parts of said transfer members moving away from the platen into a path at right angles to said superposed parts of the transfer members, and for diverting said last mentioned parts in said path, back into a superposed order toward said platen.

6. In a typewriting machine, a paper carriage including a platen, a framework mounted on said carriage and constructed to support and guide a plurality of transfer members adapted for a feeding movement with and about said platen, said framework including upwardly and outwardly inclined bars which divert said transfer members from the movement toward and away from said platen into a path parallel with said platen.

7. In a typewriting machine, a paper carriage including a platen, a framework

mounted on said carriage and constructed to support and guide a plurality of transfer members adapted for a feeding movement with and about said platen, said framework including bars which diverge upwardly from the middle of the paper carriage and direct parts of said transfer members about said platen in superposed relation and direct the other parts thereof into a path at right angles to said superposed parts and also direct said last mentioned parts at right angles to the superposed parts, back into said superposed relation.

8. In a typewriting machine, a paper carriage including a platen, a framework mounted on said carriage and constructed to support and guide a plurality of transfer members adapted for a feeding movement with and about said platen, said framework including bars which diverge upwardly from the middle of the paper carriage and which direct parts of said transfer members in a superposed relation toward and about the platen and which divert said superposed parts moving away from the platen, outwardly and into a path parallel with the platen, and means on said framework for again directing said transfer member parts moving in a path parallel with the platen back, inwardly toward each other and toward said diverging bars which again direct said transfer member parts back in superposed relation into a path moving toward said platen.

9. In a typewriting machine, a paper carriage including a platen, frame members, one fixed to each end of the paper carriage and having parts which overlap each other near the middle of the platen, said frame members being constructed to support transfer members adapted for a feeding movement with the platen, said frame members including means which direct parts of the transfer members toward and away from the platen in superposed relation and which divert said transfer member parts moving away from the platen outwardly into a path parallel with the platen, means on said frames for directing said last mentioned parts of the transfer members inwardly toward each other, said last mentioned means being arranged radially with respect to the platen, said frame members including parts for directing said last mentioned transfer member parts, back into a path moving toward the platen in superposed relation.

10. In a typewriting machine, a paper carriage including a platen, a framework mounted on said carriage and constructed to support and guide a plurality of transfer members adapted for a feeding movement with and about said platen, said framework including bars which diverge upwardly from the middle of the paper carriage and which direct parts of said transfer members in a

- superposed relation toward and about the platen and which divert said superposed parts moving away from the platen, outwardly and into a path parallel with the 5 platen, means on said framework for again directing said transfer member parts moving in a path parallel with the platen back, inwardly toward each other and toward said diverging bars which again direct said transfer member parts back in superposed relation into a path moving toward said platen, and means on said frame members for applying a tension to said transfer members. 10
11. In a typewriting machine, a paper carriage including a platen, frame members, one fixed to each end of the paper carriage and having parts which overlap each other near the middle of the platen, said frame members being constructed to support transfer members adapted for a feeding movement with the platen, said frame members including means which direct part of the transfer members toward and away from the platen in superposed relation and which 20 divert said transfer member parts moving away from the platen outwardly into a path parallel with the platen, rotary members journaled in the outer ends of said frame members for directing the last mentioned 25 parts of said transfer members inwardly toward each other, said frame members including parts for directing the said last mentioned transfer member parts back into a path moving toward the platen in superposed relation. 30
12. In a typewriting machine, a paper carriage including a platen, frame members, one fixed to each end of the paper carriage and having parts which overlap each other near the middle of the platen, said frame members being constructed to support transfer members adapted for a feeding movement with the platen, said frame members including means which direct parts of the 40 transfer members toward and away from the platen in superposed relation and which divert said transfer members parts moving away from the platen outwardly into a path parallel with the platen, cylinders of approximately the same diameter as that of the platen, journaled in the outer ends of said frame members, which direct the last mentioned parts of said transfer members inwardly toward each other, said frame members including parts for directing said last 50 mentioned parts of said transfer members back into a path moving toward the platen and in superposed relation. 55
13. In a typewriting machine, a paper carriage including a platen, frame members, one fixed to each end of the paper carriage, said frame members overlapping each other near the middle of the platen, each frame comprising upright posts, top and bottom 60 bars and inclined bars connecting said top and bottom bars, a cylinder associated with each frame and bottom bars, a cylinder associated with each frame, and means on each frame providing a bearing support for the associated cylinder. 65
14. In a typewriting machine, a paper carriage including a platen, frame members, one fixed to each end of the paper carriage, said frame members overlapping each other near the middle of the platen, each frame comprising upright posts, top and bottom 70 bars and inclined bars connecting said top and bottom bars, and top and bottom flanges between said top and bottom bars, and a cylinder associated with each frame and journaled at its ends in said top and bottom 75 flanges. 80
15. In a typewriting machine, a paper carriage including a platen, frame members, one fixed to each end of the paper carriage, said frame members overlapping each other near the middle of the platen, each frame comprising upright posts, top and bottom 85 bars and inclined bars connecting said top and bottom bars, and top and bottom flanges between said top and bottom bars, a cylinder 90 associated with each frame, and adjustable bearing sleeves on said flanges in which said cylinder is journaled. 95
16. In a typewriting machine, a paper carriage including a platen, frame members, one fixed to each end of the paper carriage, said frame members overlapping each other near the middle of the platen, each frame comprising a plate constructed to be affixed to the end of the paper carriage, a pair of 100 upright, spaced posts, top and bottom bars arranged in pairs, the pair of top bars being shorter than the pair of bottom bars, inclined bars connecting the top and bottom bars together, said inclined bars being constructed to provide shoulders near said top and bottom bars, a cylinder associated with each frame, and means on each frame providing bearings for said cylinder. 105
17. In a typewriting machine, a paper carriage including a platen, frame members, one fixed to each end of the paper carriage, said frame members overlapping each other near the middle of the platen, each frame comprising a plate constructed to be affixed to the end of the paper carriage, a pair of 110 upright, spaced posts, top and bottom bars arranged in pairs, the pair of top bars being shorter than the pair of bottom bars, inclined bars connecting the top and bottom bars together, said inclined bars being constructed to provide shoulders near said top and bottom bars, brace bars connecting the bottom bars and inclined bars together, a cylinder associated with each frame, each frame including top and bottom flanges, and means associated with said flanges providing adjustable bearings for said cylinder. 115
18. In a typewriting machine, a paper carriage including a platen, frame members, 120

one fixed to each end of the paper carriage, said frames overlapping each other at their bottom ends near the middle of the platen, each frame comprising upright posts, top 5 and bottom bars, and inclined bars connecting said top and bottom bars, a vertically disposed cylinder journaled in each frame, and a horizontal bar having a tearing edge connecting the top bars on the front of the 10 frame members together.

19. In a typewriting machine, a paper carriage including a platen, frame members fixed to the ends of the paper carriage and overlapping each other near the middle of 15 the platen, said frames comprising upright posts arranged in pairs, top and bottom bars arranged in pairs, and inclined bars connecting the bars of each pair of top and bottom bars together, a brace bar connecting the 20 front top bars of the said frames together, said brace bar having a tearing edge and

two slots therein, and an upright cylinder journaled in each frame near said posts.

20. A frame adapted to be attached to the paper carriage of a typewriter, said frame 25 comprising a plate, upright spaced posts, top and bottom, horizontally arranged, spaced bars, the said top bars being shorter than the said bottom bars, inclined bars having shoulders, connecting the ends of said 30 top and bottom bars together, flanges at the top and bottom of said frame, and means associated with said flanges providing a bearing for a cylinder.

In testimony, that I claim the foregoing 35 as my invention I affix my signature in the presence of two witnesses, this 16th day of October A. D. 1916.

EDWARD ZUVER LEWIS.

Witnesses:

T. H. ALFREDS,
KARL M. DOLL.
